BILLFOLD

William R. Whitmer, Springfield, Ohio, assignor
to The Springfield Leather Products Company,
Springfield, Ohio, a corporation of Ohio

Application June 1, 1949, Serial No. 96,519

5 Claims. (Cl. 150—38)

1

This invention relates to pocket wallets or billfolds. More particularly, it relates to billfolds whose construction provides complete interlocking walls to form an expandable gusset-like structure.

Interlocking walls in billfolds have been used before. In one particular style of billfold the arm member forming the end of the billfold interlocks into the face of the inner wall.

This construction suffers from the disadvantage that additional tacking or holding means is required to prevent the arm member from flaring outwardly and destroying the neat appearance of the billfold.

These methods of controlling and biasing the gusset walls to always lie inwardly directed have presented the leather goods industry with a vexing problem.

It is an object of the present invention to provide a new billfold which will avoid the difficulties and limitations of the prior billfolds as pointed out above.

It is an object of the present invention to provide a billfold having an accordion style of construction.

It is another object of the present invention to provide a billfold with expandable end walls formed of portions, each attached to separate wall sections, which are always held in gusset style with the apex directed inwardly.

It is a further object of the present invention to provide a billfold having expandable end walls produced by the interlocking of portions of the inner and outer wall members.

It is a still further object of the present invention to provide, when desired, a wallet having portions foldable to provide a simplified arrangement in providing for a hidden or secret pocket for bills and papers, which can also provide dual open top compartments.

It is another object of the present invention to provide a billfold which may be assembled as a compact unit without stitching any part of the basic wall sections.

It is another object of the present invention to provide a billfold having interlocking members without the interlocking being apparent from the exterior.

Further objects and advantages will be apparent from the following description:

Billfolds of this invention are constructed with closed end structure formed by the interlocking of members which are an integral part of the outer and inner walls.

As far as is known, such construction giving the expandable features of gussets has never been formed with the main portion of the body of the billfold in a manner whereby the interlocking structure is unobvious except when the expanded billfold is viewed from the end.

2

The advantages of this new construction at once become apparent. The pocket wallet is inexpensive to assemble, requiring merely folding and interlocking of the respective sections or portions.

The end of the billfold is closed by end pieces acting in the nature of gusset walls to allow expansion without the possibility of the billfold becoming out of shape.

10 The way in which the new and novel billfold of applicant is constructed will be better understood by reference to the following description and the drawings.

In the drawings:

15 Figure 1 is a view of the basic blank of the billfold adapted to have a built-in secret pocket;

Figure 2 is a top view of a basic bridging wall;

20 Figure 3 is a top view of an auxiliary wall which may be sewed or otherwise fastened to the basic blank when building a hidden pocket into the billfold;

Figure 4 is a view of the basic blank for a wallet without a hidden pocket laid out in a single plane corresponding to Figure 1;

25 Figure 5 is a top view of the bridging wall identical with Figure 2, but to be used in conjunction with the basic blank of Figure 4;

Figure 6 is a horizontal cross sectional view of the folded billfold of Figure 1 along its central axis;

30 Figure 7 is an elevational view of the assembled billfold of Figure 1 partially cut away to disclose interlocking features;

Figure 8 is a horizontal cross sectional view of 35 the billfold of Figure 4 without the additional partition dividing the interior of the billfold into an open and a hidden pocket;

Figure 9 is an elevational view of the assembled billfold of Figure 4 partially in section to show 40 the folding construction;

Figure 10 is a vertical cross sectional view of the billfold taken along the line 10—10 of Figure 7;

Figure 11 is a vertical cross sectional view of 45 the billfold taken along the line 11—11 of Figure 7;

Figure 12 is a vertical cross sectional view of a modified billfold construction taken as along the line 12—12 of Figure 7 showing a folded bottom gusset instead of a rounded bottom;

50 Figure 13 is a vertical cross sectional view of a billfold taken along the line 13—13 of Figure 9;

Figure 14 is a vertical cross sectional view of a billfold taken along the line 14—14 of Figure 9;

Figure 15 is a vertical cross sectional view of a billfold taken along the line 15—15 of Figure 9;

Figure 16 is a fragmentary plan view showing the interlocking feature forming the closed end of the billfold; and

60 Figure 17 is a fragmentary plan view showing

the arrangement whereby the bridging member of Figure 2 is attached to the inner wall of the blank of either Figure 2 or Figure 4.

Referring to the drawings, the billfold of this invention consists in its basic form shown in Figures 1 and 4 of an outer rear wall 20, whose dimensions within the hereinafter explained folds, establishes the external dimensions of the billfold.

An inner wall 21 consists of two longitudinally spaced sections 22 and 23, which are integral with the outer wall section 20 and joined thereto along the bottom fold 24. Between sections 22 and 23 there is a small flap 25 for a purpose hereinafter explained.

The principal difference between the basic forms is to be found in the type of flap attached to the outer wall 20 opposite the bottom fold 24 and adapted to lie along the inside face of said outer wall.

Figure 1 illustrates the flap utilized to conceal the hidden pocket. This flap is composed of three portions, 26, 27 and 28 joined to the outer wall along the fold 29.

Portions 26 and 28 are adapted for being turned semi-permanently inward, while portion 27 is for use as a cover for the hidden pocket.

On the other hand, the flap 30 in the basic structure of Figure 4 is a unitary piece joined to the outer wall along the fold 31 and adapted to lie against the inside face of said outer wall to accomplish any one or more effects such as stiffening, finishing, or even if of proper length, to provide a concealed pocket.

Sections 22 and 23 have integral wall sections 32 and 33, respectively, which fold along the fold line 34 in order to lie against the inside of sections 22 and 23, thus forming a tubular structure adapted to enclose a bridging wall 35.

Sections 32 and 33 are each provided with companion perforations 36, whose purpose will be hereinafter explained, but which merely illustrate one means of accomplishing the attachment of a hereinafter discussed bridging wall.

Adjacent the lateral side sections 32 and 33 are incised to produce retainer arms or tongues 37 and 38.

Arms 37 and 38 are provided with throat portions 39 and 40 which extend through herein-after explained slots. These throat portions 39 and 40 are provided with laterally extending ears 50 and 51, respectively, which prevent the throat portions 39 and 40 from being readily withdrawn from the slots through which they extend.

Outer wall 20 is provided along side edges 52 and 53 with integral flaps 54 and 55, respectively. Flaps 54 and 55 are vertically slit as at 56 and 57.

Inner wall sections 22 and 23 are provided along the side edges 58, 59 with integral flaps 60 and 61, respectively. Flaps 60 and 61 are apertured as at 62 and 63, and adapted for loose sliding fit with the throat of arms 37 and 38.

Bridging wall section 35, illustrated in Figure 2, is a flexible unit of slightly shorter length than the inner wall 21.

Wall 35 is provided with two pairs of parallel apertures 64 and 65 defining stem sections 66 and 67 which terminate in convexly shaped end sections 68 and 69 creating retainer tabs 70 and 71 for locking bridging wall 35 to inner wall flaps 32 and 33.

In Figure 3 there is illustrated the blind wall 72 forming a divider separating the pocket of

the billfold into an exposed and a hidden pocket.

Wall 72 is bound along the dotted line 73 to that portion of wall sections 32 and 33 indicated by the dotted line 74. The binding is accomplished by sewing or other suitable means.

The billfold formed from the basic structure of Figures 4 and 5 is illustrated in Figure 9. In this Figure 9 wall sections 32 and 33 are shown folded over to enclose bridging wall 35.

As will be seen in this figure and by reference to Figure 17, the bridging wall 35 is suspended from and forms a link between sections 32 and 33 by means of retainer tabs 70 and 71 which are passed through the twin apertures 36 and are held in loose sliding relationship by heads 68 and 69.

Flap section 30 is shown folded down against the inner side of outer wall 20. The end flaps 54 and 55 of the outer wall 20 and flaps 60 and 61 of the inner wall 21 are folded inwardly.

Retainer flap 37 is passed through the aperture 62 of flap 60 and the throat is extended or inserted through slit 56 in flap 54. Correspondingly, retainer flap 38 is passed through the aperture 63 of flap 61 and the throat is extended or inserted through slit 57.

In this way the inner wall slides loosely on the retainer flap throat giving the structure flexibility while the two flaps are always held in an inwardly extending position.

The lateral relationship of the various portions is better understood by reference to Figure 8, wherein it will be seen that the flaps 54 and 60 lie back to back with retainer flap 37 passing therethrough to lie against the inner side of outer wall 20. At the opposite end the corresponding parts are similarly interlocked.

It is also apparent here that the bridging wall 35 lies against the inner side of wall sections 22 and 23 and closes the space between these sections.

This construction is further illustrated in Figure 16 where the head of the retainer flap is shown lying adjacent flap 54 with the throat passing through slit 56, from whence it passes through slit 62 in flap 60.

The vertical alignment is further brought out in Figures 13, 14 and 15, wherein it will be seen that flap 30 lies against the inner side of outer wall 20, and that flap 25 merely folds inwardly into the billfold compartment.

The billfold formed from the basic structure of Figures 1, 2, and 3 is illustrated in Figure 7. In this Figure 7 wall sections 32 and 33 are shown folded over to enclose bridging wall 35.

The bridging wall, as in the billfold of Figure 9, is suspended from and forms the link between sections 32 and 33. However, in this billfold the blind wall 72 is shown lying against the opposite side of walls 32 and 33 from the bridging wall 35 and is attached thereto along the dotted line 74 by sewing. Thus, when wall sections 32 and 33 are folded inwardly blind wall 72 lies against the inner side of outer wall 20.

Flap sections 26, 27 and 28 are shown folded down with section 27 covering the top of blind wall 72 and forming a closure for a so-called hidden pocket.

In these figures it will be seen that the end flaps attached to both the inner and outer walls are folded inwardly and interlocked in the same manner as has been described in connection with the billfold of Figures 4 and 9.

The lateral relationship of the various portions of the billfold of Figure 7 is better understood

from Figure 6 wherein it will be seen that flaps 54 and 60 lie back to back with retainer flap 37 passing therethrough to lie against the inner side of outer wall 20. At the opposite end of the billfold the corresponding parts are similarly interlocked.

It is also apparent here that the bridging wall 35 lies against the inner side of wall sections 22 and 23 and closes the space between these sections.

The vertical alignment is further brought out in Figures 10, 11 and 12 wherein it will be seen that flap sections 26, 27 and 28 are folded inwardly with the flap section 27 overlying the upper end of the blind wall 72. The lower end of the blind wall 72 is attached to the lower end of integral wall sections 32 and 33.

Also, it will be seen that while the inner wall is composed of longitudinally separated portions, view into the hidden pocket is obstructed by the combination of small flap 25 folded inwardly, particularly as illustrated in Figure 10.

In Figure 12, a construction is shown wherein a foldable section 80 is provided between outer wall 20 and inner wall 23. This section 80 is turned inwardly with the apex at 81 and formed with legs 82 and 83 having substantially any relative proportions. This inwardly biased bottom gusset gives the billfold even expandability over its entire length.

While the billfolds disclosed and described herein constitute preferred forms of the invention, yet it will be understood that the device is capable of alteration without departing from the spirit of the invention, and that all modifications which fall within the scope of the appended claims are intended to be included herein.

For example, those skilled in the art will recognize that the flaps 54 and 55 formed integral with outer wall 20, and flaps 60 and 61 formed integral with inner wall 21, may be sewed together and the gusset like structure held biased in inwardly position by the tongue 37 or 38 of the fold-over flaps 32 and 33.

It will also be recognized that the shape of these flaps may be altered. For example, flaps 54 and 55 may be of such length that the flaps may be doubled back enclosing the flaps 60 and 61 when the billfold is assembled.

It will at once be recognized that this necessitates that flaps 54 or 55 be apertured in two places so that the tongue 37 or 38 may be extended through the three thicknesses of leather formed as the gusset wall. Such a construction for some uses may be an advantage by creating a stiffer structure.

I claim:

1. A billfold comprising an outer wall, an inner wall integral with said outer wall and having fold-over flap sections positioned to lie between said inner and outer walls, said fold-over sections being provided with retainer tabs, and an end flap at each end of said outer and inner walls having slot means to receive said retainer tabs for locking together each pair of flaps.

2. A billfold comprising an outer wall having a top flap, an inner wall integral with said outer wall consisting of two longitudinally spaced sections having fold-over flap sections positioned to lie between the said inner and outer walls, said fold-over sections each having a retainer tab adjacent the outer end of each section and pairs of apertures, a wall closure member disposed between said fold-over sections and inner wall and provided with retainer flaps at opposite

ends thereof and held in position with limited longitudinal sliding action by the retainer flaps extending through said apertures in said fold-over sections, a side flap at each end of said outer wall and said inner wall section folded inwardly and having slot means therein receiving the retainer tab of said fold-over sections to interlock said side flaps to said fold-over section, a currency compartment divider connected to the bottom edge of said fold-over sections and held in position by its top portion enclosed between said top flap and said outer wall.

3. A billfold comprising an outer longitudinally extending wall, an inner wall integral with said outer wall and extending therewith and having fold-over flap portions positioned to lie between said inner and outer walls, said fold-over sections being provided with retainer tabs extending substantially transversely to said longitudinally extending walls, and an end flap at each end of said outer and inner walls having slot means extending substantially transversely in said walls to receive said retainer tabs for locking together each pair of flaps.

4. A billfold comprising an outer longitudinally extending wall, an inner wall integral with said outer wall and extending therewith and having fold-over flap sections positioned to lie between said inner and outer walls, said fold-over sections being provided with retainer tabs extending substantially transversely of said walls, and an end flap at each end of said inner and outer walls having slot means extending transversely in said walls to receive said retainer tabs for locking together each pair of flaps, said slot means of said outer wall being positioned outwardly of said slot means of said inner wall.

5. A billfold comprising an outer wall having a top flap, an inner wall integral with said outer wall and having a fold-over flap section positioned to lie between the said inner and outer walls, said fold-over section having retainer means adjacent the outer ends thereof, a side flap at each end of said outer and said inner wall folded inwardly and having retaining means therein cooperating with the retaining means of said fold-over sections to interlock said side flaps with said fold-over section, and a currency compartment divider connected to the bottom edge of said fold-over section and held in position by its top portion enclosed between the said top flap and the said outer wall.

WILLIAM R. WHITMER.
